UNITED STATES PATENT OFFICE.

WILLEM JOHANNES GIEL, OF THE HAGUE, NETHERLANDS.

TYPE-WRITER.

1,108,742.

Specification of Letters Patent. Patented Aug. 25, 1914.

Application filed October 8, 1912. Serial No. 724,660.

To all whom it may concern:

Be it known that I, WILLEM JOHANNES GIEL, retired colonel of the Royal Dutch Army, subject of the Kingdom of the Netherlands, residing at 100 Schuytsstraat, The Hague, Kingdom of the Netherlands, have invented certain new and useful improvements in Type-Writers, of which the following is a specification.

- 10 In typewriters provided with type by means of which the impressions are made upon the paper and which are formed with a plate, a sector or a roller, such type are arranged on the latter in horizontal rows one 15 below the other and are brought by means of key-actuated levers to the proper level for printing, that is to say, into the position required for making the impressions in the line of writing. By means of such typewriters 20 the letters, figures and other characters can be printed as a rule only in a horizontal line, one after another, the impression being made by depressing a key, during the subsequent upward movement of which the paper 25 is carried forward and moved into that position which it is necessary for it to occupy in order to receive the next impression, that is, the impression of the following letter, figure or other character. Again, most typewriters of the character just referred to are 30 furthermore fitted with a special key by means of which the paper is moved back in a horizontal direction, so that the forward movement of the paper is interrupted. This 35 special key is commonly called the back-space key. Furthermore, in order to produce an impression the proper and normal position of which is above the line of writing, the paper has in typewriters of this 40 kind to be adjusted. In the case of languages using roman letters or characters, only a few of which consist of two parts superimposed upon or adjacent to each other, the letters, figures or other characters may 45 without any special adjustment of the paper be brought directly to the proper level and imprinted, one after the other, which results from the fact that separate keys can be arranged for these few peculiar characters 50 that have to be printed above or below the line of writing. If, however, several letters or figures or other characters are required to be arranged in superposition with respect to one another, the paper has to be 55 adjusted in a vertical direction after the

making of each impression. Again, the paper, which after the printing or typing has already been fed automatically into the position required for the printing of the next succeeding character, must be pushed back 60 just enough so that it will again occupy the position last occupied, the automatic advance movement of the paper being thus interrupted. In the case of many monosyllabic languages of the countries of the 65 East (for example, the Javanese language), in which certain characters frequently consist of from two to four parts arranged vertically one above the other, the adjustment just referred to presents much greater difficulties, since the time-consuming manipulations of positioning the paper both horizontally and vertically must be performed repeatedly.

The object of the present invention is to 70 overcome and avoid the aforementioned drawbacks met with in the use of typewriters in which the type letters, figures or other signs or characters by means of which the impressions are made and which are arranged in rows, one below the other on a plate, a sector or a-wheel, and to provide a typewriter by means of which the letters, figures or other signs and characters can be 75 printed in superposition with respect to one another and superposed in any required 80 number. In this way such a language as the Javanese language can be typewritten without special effort or loss of time. This object is attained by so arranging the type-carrying plate, roller, sector or its equivalent (commonly called, I believe, the type-shuttle) and its actuating parts, that by 85 simply touching one of the keys by means of which the impression of a type character is obtained, the said impression or imprint is properly positioned either on or above or below the line of writing. Then by depressing one of the keys by means of which the rows of type characters are adjusted or positioned, the paper is simultaneously and automatically pushed back such a distance or interval that the paper is again brought 90 into the position in which it was required to be for the production of the impression last made. Owing to the peculiar arrangement of this type-shuttle, the extra adjustment of the paper in a vertical direction is avoided; for, by connecting the so-called shift-keys 95 used for making the adjustment of the rows, 100 105 110

with the so-called back-space key, there is avoided an extra actuation of the latter key for the production of characters consisting of several parts superposed on one another.

5 By practically grouping the figures, letters or other signs or characters in various rows, the result is attained that, by the special arrangement of the shift-keys, no more manipulations are required for writing a language, such as the Javanese, than are required in the case of writing a language in which are used roman characters.

One practical embodiment of this invention is exemplified in the accompanying drawing, which is intended especially to show a typewriter fitted with a type-shuttle arranged for writing roman characters but altered in such a manner that it can be used as well for printing impressions of 10 Javanese letters, figures and other signs and characters.

In the drawings illustrating the principle of this invention and the best mode now known to me of applying that principle, 15 Figure 1 shows in elevation a type-shuttle and its actuating key as these parts are arranged in an ordinary typewriter for use in printing roman letters and characters; Fig. 2 shows in elevation a type-shuttle made in accordance with the present invention; Fig. 25 3 is a detail showing in plan the interconnection between the back-space key and the other keys; Fig. 3^a is a side view of the parts shown in Fig. 3, the view being taken looking to the right in Fig. 3 and the back-space key 12 being omitted; and Fig. 4 is a detail showing the back-space key in side view.

In Fig. 1, the type 2 are arranged on the type-shuttle 1 in three rows 5, 6, 7, of which 20 the row 5 is in position for printing without displacing the type-shuttle vertically. In order that impressions may be made of the characters arranged in rows 6 and 7, the type-shuttle is displaced vertically upward by means of keys one of which is shown at 25 3, 4, Fig. 1. This is the arrangement which has customarily been used heretofore in this class of typewriters. According to the present invention the type-shuttle shown in Fig. 50 1 is replaced by the type-shuttle illustrated in Fig. 2, the type face of which may be regarded as divided into three equal horizontal parts or spaces 8, 9, 10. However, in these spaces the characters are not necessarily on the same horizontal lines or in the same horizontal row. For example, in the space 10 the characters are distributed in four horizontal rows, which arrangement is adopted in this particular case by reason of 55 the fact that in the Javanese language the greatest number of parts of which a single character is composed is four. When the characters the position of which is to be in the line of writing are arranged in the second line or level, the characters which are

to print above the line of writing are preferably arranged in the first level and those which are to print below the line of writing are arranged in the third and fourth levels.

In grouping the characters it is preferable to place in the first space 8 as many as practicable of those characters which are to print directly in the line of writing and to place in the second and third spaces 9, 10, those characters which are to print below the line of writing or above it. Since when writing roman characters there will also always be provided one of the shift-keys for producing the impressions of the characters occurring in the second and third spaces, the 70 typing of these special characters will not be accompanied by any peculiar trouble, difficulty or loss of time in connection with a typewriter embodying the present invention; the principal point is that the moving 75 back of the paper, the operation of the back-space key and the adjustment of the required row can be produced by a single movement. For this purpose there is provided in addition to the back-space key, 80 with which most typewriters of this class are now fitted, a set of levers less in number than the number of spaces into which the type-shuttle is divided.

In Fig. 3 there is shown an arrangement 85 in which there are two levers 13, 14 arranged to coact with the ordinary back-space key 12. Below these levers 13, 14 there is arranged a lever 16 that actuates the rod which displaces the type-shuttle, 100 the levers 13 and 14 being provided with contact pieces at such a level that by depressing the key of the lever 13 and by forcing down the lever 14 the third space of the type-shuttle is brought into printing position. Moreover, the back-space key 12 is formed at one side with a lug 17 and the lever 13 is provided on its face adjacent to the back-space key with a pawl or detent 18 arranged to engage the lug 17. The frame 110 of the machine carries a tripping-screw 19 one end of which is projected into the path of the detent 18 so that, upon the depressing of the lever 13 the detent 18 is swung on its pivot and is thereby disengaged from the lug 17. The lever 14 is provided with a laterally-extending tongue 20 which projects over the lever 13, so that when the lever 14 is depressed, the lever 13 is also depressed and the back-space key 12 is actuated. However, it is obvious that when the lever 13 is depressed, it will move independently of the lever 14. From this arrangement of parts it results that, when either of the levers 13 or 14 is actuated, the back-space 125 key will also be actuated and the paper will be moved back to the position which it occupied at the time that the last impression was made; and the trip-screw 19 is so adjusted that the lug 17 is not disengaged 130

from the detent 18 until the back-space key has come into action and the paper has been pushed back over the required distance.

As hereinbefore described, the typewriter 5 has been arranged for printing characters one above the other in vertical columns; however, when the characters are to be printed in oblique columns, the type must not be placed vertically as hereinbefore de- 10 scribed and shown in the drawings, but the type should be placed in inclined lines or columns.

In case of a typewriter embodying the present invention, the surface must evi- 15 dently be of a size sufficient to enable the printing of the type characters which occur in the different levels or horizontal lines.

In the case of typewriters in which the 20 impressions are made by means of a roller which carries the type (that is, a type-wheel) being brought forcibly against the paper, this roller is concaved out all over its periphery at each row of type characters 25 so as to correspond to the curvature of the paper roller or platen, the type characters being placed in stepped relation in this concaved face. The levers 13, 14 may also be directly connected with the paper-carrying 30 carriage, in which case they must be fitted with a device for back-spacing the paper. In that case the levers are not connected with the back-space key, from which it results that in the case of typewriters having 35 no back-space key the embodiment of the same therein may be entirely dispensed with.

In the case of typewriters provided with shift-keys which serve only for adjusting the rows, these shift-keys may be coupled 40 up with the back-space key so that no special shift-keys 13, 14 will in that event be required.

The advantages resulting from the use of the present invention, particularly as far as 45 economy of time is concerned, will be clearly understood from the following comparison between old style typewriters and type-

writers embodying the present invention. Let it be supposed that the two letters, "a" and "b," are to be printed in superposition. 50 In order to effect this result by means of the old style typewriter it is required: (1) to depress the "a" key; (2) to adjust the paper in a vertical direction; (3) to actuate the back-space key; (4) to actuate the shift-key; and (5) to depress the "b" key. In using a typewriter embodying the present invention all that it is necessary to do to effect this same result is: (1) to depress the "a" key; (2) to actuate the shift-key connected with the back-space; and (3) to depress the "b" key. Thus, in the case of a typewriter embodying the present invention, not a single movement more has to be performed than in the case of operating an 65 old style typewriter to print two letters or characters one after the other in the usual way.

I claim:

1. In a typewriting machine, the combination of a type-shuttle, a shift-key therefor, a back-space-key arranged to interlock with said shift-key; and means for disconnecting said keys after the paper has been brought back to the position which it occupied at the 70 printing of the character last printed.

2. In a typewriting machine, the combination with a back-space key; of a shift lever provided with a detent adapted to engage said back-space key. 75

3. In a typewriting machine, the combination with a back-space key; of a pair of shift levers, one of which is provided with means for engaging said back-space key and the other of which is provided with 80 means for engaging its cooperating shift lever.

In testimony whereof I have affixed my signature in presence of two witnesses:

WILLEM JOHANNES UER.
